UNITED STATES PATENT OFFICE.

MORRIS WEINGARTEN, OF NEW YORK, N. Y.

ADJUSTABLE FOOTSTOOL.

1,402,698.

Specification of Letters Patent.

Patented Jan. 3, 1922.

Application filed June 25, 1921. Serial No. 480,287.

To all whom it may concern:

Be it known that I, MORRIS WEINGARTEN, a citizen of the United States, and a resident of the city of New York, borough of 5 Manhattan, in the county and State of New York, have invented a new and Improved Adjustable Footstool, of which the following is a full, clear, and exact description.

This invention relates to an adjustable support and has particular reference to an adjustable footstool adapted for use in connection with chairs especially in stores or shops.

An object of the invention is to provide a 15 simple and efficient stool which can be readily disposed in a convenient place out of the way when not in use but which can be readily adjusted in an operative usable position especially with reference to the chair or 20 other support when it is desired to use it.

A further object resides in the provision of simple, rugged, economically manufactured apparatus whereby the stool can be adjusted in accordance with the object above 25 set forth.

A further object resides in the provision of the particular construction and arrangement of parts hereinafter described and claimed and shown in the accompanying 30 drawing.

In general the invention relates to an ordinary support, preferably in the form of a stool, which is adapted to be used in connection or conjunction with a chair especially 35 in shoe-stores or other places where persons sitting in chairs desire to rest their feet on something. Under ordinary circumstances, it is found that if these stools or rests are left indiscriminately around the 40 shop or room, they are very much in the way and are a constant annoyance. However, by applying very simple and easily operated means to the stool, I have provided that it can be placed beneath a chair or 45 other device with which it is associated, and then when it is desired to use the stool, it can readily be pulled out to an operative position. This constant and intimate association of the stool with the chair tends to 50 prevent it from being lost or from getting out of place, and thus avoids the necessity of constantly replacing it.

The invention is illustrated in the drawing, of which—

55 Figure 1 is a side view of a chair showing

the stool in section beneath the chair and in dotted lines in its operative position, together with the means connecting it to a fixed bracket beneath the chair;

Fig. 2 is a plan view of the device;

Fig. 3 is a section taken on the line 3—3 of Fig. 2.

As shown in the drawing, the preferred form of my invention is applicable to and associated with an ordinary chair or other 65 support 1.

The invention comprises a stool or rest 2 of any suitable type and design, to which an ordinary mechanism 3, known as lazy tongs, is connected. The connection is preferably by means of a plate 4 which may be fastened along and underneath an edge of the stool and is of any used construction. This plate is provided with a slot 5 in which one end 6 of one of the links, such as 7, of the lazy tongs can slide. The end 8 of another link 9 of the lazy tongs is rigidly connected to the plate 4. This plate can be fastened by any suitable means, such as screws 10, to the stool 2.

The other end of the lazy tongs 3 is connected to a plate 11 in a manner identical with its connection to the plate 4 at the other end of the lazy tongs, and this plate is connected or suitably supported on a pair 85 of bracket arms or frame members 12. These bracket arms or frame members are rigidly connected to either the floor in a position preferably beneath the chair 1, or may be connected, if desired, to the chair, although 90 this latter modification is not shown.

It is therefore readily perceived in accordance with the illustration of Fig. 1, that when the lazy tongs 3 is drawn into its collapsed or its retracted position, the stool 2 95 is disposed beneath the chair 1 out of the way, and yet is instantly available to be pulled out into the position shown in dotted lines in Fig. 1, whenever desired. In this way a convenient stool is associated with 100 each chair or with any particular fixed location whether there is a chair there or not, and, therefore, cannot be indiscriminately moved around and get in the way, causing unnecessary annoyance.

It is of course understood that the usual application of this invention is concerned with its relation to a chair or other support, but, at the same time, the main essence of the invention resides in the fact that the 110

stool is adjustably related to some fixed point on a rigid support whether that support be a floor, a wall, or in association with a chair.

I claim—

- 5 An adjustable stool for use in association with a chair or other device, a pair of bracket members disposed beneath the chair and spaced apart, a bar having a slot therein con-

necting the upper ends of the bracket members, a plate disposed along the rear under surface of the stool and having a slot therein, and a lazy-tong mechanism connecting the two plates and having members slidable in said slots whereby the stool can be pulled out from beneath the chair for use as desired.

MORRIS WEINGARTEN.
